UNITED STATES PATENT OFFICE.

WILLIAM R. JEAVONS, OF CLEVELAND, OHIO.

DESIGN FOR A STOVE-WINDOW.

45,384.

Specification for Design.

Patented Mar. 10, 1914.

Application filed December 31, 1913. Serial No. 809,754. Term of patent 14 years.

To all whom it may concern:

Be it known that I, WILLIAM R. JEAVONS, a citizen of the United States, residing at Cleveland, in the county of Cuyahoga and State of Ohio, have invented a new, original, and ornamental Design for Stove-Windows, of which the following is a specification, reference being had to the accompanying drawing, forming part hereof, wherein—

Figure 1 represents a front elevation of such window, the stove drum being indicated in broken lines; Fig. 2 a sectional view corresponding to the line 2—2 of Fig. 1 and

looking in the direction of the arrows, a part of the drum being indicated by the broken lines; Fig. 3 a vertical sectional view corresponding to the line 3—3 of Fig. 1 and looking in the direction of the arrows the stove drum being indicated by the broken line.

I claim:—

The ornamental design for a stove window, as shown.

WILLIAM R. JEAVONS.
